UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,424,046.

Specification of Letters Patent.

Patented July 25, 1922.

Application filed December 16, 1921. Serial No. 522,738.

To all whom it may concern:

Be it known that I, ELMER B. STONE, a citizen of the United States, residing in New Britain, in the county of Hartford and 5 State of Connecticut, have invented new and Improved Locks, of which the following is a specification.

My invention relates to that class of locks comprising a yoke or shackle that is secured 10 in locked position by means of the lock mechanism, such invention relating more especially to such class of locks in which the yoke or shackle projects entirely through the lock case, and an object of my invention, 15 among others, is to provide a lock of this latter type, in which the key for operating the locking mechanism may be in a convenient and accessible position.

One form of lock embodying my invention and in the construction and use of which the objects herein set out, as well as others, 20 may be attained, is illustrated in the accompanying drawings, in which—

Figure 1 is a face view of my improved 25 lock.

Figure 2 is an edge view of the same.

Figure 3 is a view similar to Figure 1 with a portion of the case removed and showing the lock mechanism.

Figure 4 is a detail view illustrating a 30 little different manner of engagement of the locking bolt with the shackle.

My invention has particularly to do with a lock having a long yoke or shackle as compared with other types of locks, which long shackle is of advantage in securing automobiles so that they may not be moved. In prior locks of this type the keyhole has been so located with respect to the arms of the shackle as to make manipulation of the key 35 awkward and difficult. My improved lock does away with these objectionable features and is so constructed that the arms of the shackle do not interfere with the operation 40 of the key, such lock as herein illustrated, including a case comprising a stem portion 5 and a cross portion 6 located at the end of the stem portion, the projecting ends of the cross portion constituting wings 7 having 45 openings 8 extending therethrough to receive arms 9 of the shackle. This shackle is in the form of a yoke including a bend 10, the opposite end being open, that is the arms are separated and extend in substantially 50 parallel relation one with respect to another.

Notches 11 are formed on the arms, preferably facing each other, these notches being adapted to receive the ends 12 of locking bolts 13 constituting a part of the lock mechanism.

An important feature of my invention resides in such formation of the lock case that the stem 5 is located at an angle to the cross portion 6 and the wings 7. The key hole 14 is formed in the end of the stem 5, 60 the angular relation of which with respect to the cross portion, and consequently with respect to the arms 9 of the shackle that projects through the wings 7, causes the key to be located outside of the space between 65 the arms, and as illustrated in Figure 2 of the drawings, whereby the arms do not interfere with the free turning movement of the key to operate the lock mechanism.

This mechanism is located principally in 70 the stem 5 and may be of various forms and construction. That herein illustrated is found to satisfactorily serve the purpose and comprises a collar 15 having the key slot 14 shaped to permit insertion of a key of 75 special construction only. A ward 17 in the form of a bar extending across the chamber 18 has a recess 19 to receive the key, the bar being of a thickness to be received with 80 in the notches in the wards of the key in 85 a manner that will be readily understood. A bar 20 also extends across the chamber 18 and is provided with grooves 21 constituting wards to operate in connection 90 with the wards on the key. The locking 95 bolts 13 are located in the bolt chamber 22 between the bar 20 and the end of the case, and as illustrated in Figure 3 of the drawings, a recess 24 in the wall of the chamber 22 being formed to receive the end of the key and comprising a support therefor in 100 its operation.

The bodies of the bolts 13 are formed and located so that their flat sides directly face the key opening into the end of the stem, 105 such flat sides consequently being at an oblique angle to a plane passing centrally in a longitudinal direction along the arms 9. These bolts have shouldered openings through which the key passes, the shoulders 110 being adapted to receive the wards on the key in a manner common to lock structures and as will be readily understood by those skilled in the art, the contact of the wards with these shoulders, when the key is turned,

causing the bolts to be thrown backwardly and out of contact with the notches in the arms of the shackle. Springs 25 are employed to hold the bolts in a position with 5 the ends 12 normally engaged with the notches in the shackle arms.

The notches 11 in the shackle arms are beveled on one side with shoulders at the ends of the beveled parts, and the ends 12 10 of the locking bolts are correspondingly beveled so that the shackle may be pushed into the lock, the locking bolts retreating to permit such movement, but reverse movement of the shackle will be prevented by 15 engagement of the shoulders of the recesses with the flat unbeveled portions of the ends 12. The ends 12 of the locking bolts are located at an angle to the bodies of said bolts and crosswise thereof, which structure might 20 be obtained by slightly twisting the ends on their axes. This provides that the flat faces of the ends will squarely engage the shoulders of the recesses in the shackle arms, which shoulders are angularly disposed with 25 respect to the axis of the key when the latter is in position in the lock and consequently with respect to the lock mechanism that conforms to the position of the key. It will be understood that this angular formation 30 of the ends of the bolts may be obtained in various ways, depending upon the manner in which the bolts are made.

In that form of the device as illustrated in Figure 4 of the drawing, the ends of the 35 locking bolts 26 are in the same plane as the bodies of said bolts, that is, said ends are not twisted as in the forms hereinbefore described, and the recesses 27 in the shackle arms are inclined to receive the ends 40 of said bolts.

In accordance with the provisions of the patent statutes I have described the principles of operation of my invention, together with the device which I now consider to represent the best embodiment 45 thereof; but I desire to have it understood that the device shown is only illustrative, and that the invention may be carried out by other means.

50 I claim—

1. A lock including a case having an opening therein, a shackle comprising arms projecting from said opening, said case having a key opening with its lengthwise 55 center projecting at an oblique angle to said

shackle, and mechanism within said case and including a member to engage and hold said shackle.

2. A lock case including a portion with an opening for a shackle and another portion located at an oblique angle to the first mentioned portion and having a key opening arranged at an oblique angle to said shackle opening, a shackle comprising an arm projecting from said opening, and 65 mechanism within said case to be operated by a key within said key opening, said mechanism including a member to engage and hold said shackle arm.

3. A lock case including a stem member 70 and a cross member providing wings on opposite sides of said case, said members being located at an oblique angle each to the other, a shackle comprising arms extending through the wings on opposite sides of 75 said stem, mechanism located in said stem to be operated by a key positioned at an oblique angle to said shackle arms, and members included in said mechanism and adapted to engage and hold said shackle 80 arms.

4. A lock comprising a case with a shackle opening therein, a shackle extending from said opening, and comprising arms having notches with locking shoulders, lock 85 mechanism located in said case and arranged in a plane oblique to the plane of said arms, said mechanism including a bolt, and said bolt and shoulder being arranged to squarely engage each other. 90

5. A lock comprising a case with shackle openings extending therethrough near opposite edges thereof, a shackle comprising arms projecting from said openings and having square locking shoulders, lock 95 mechanism including key receiving means to locate a key with its axis at an oblique angle to a plane passing centrally through said shackle openings, said lock mechanism also including a bolt with its end twisted 100 at an angle to the plane of movement of said bolt to squarely engage with said shoulders.

6. A lock including a case, a shackle projecting from said case and including a pair 105 of arms, mechanism within the case, and means to permit insertion of a key at an oblique angle to the plane of said arms.

ELMER B. STONE.
